UNITED STATES PATENT OFFICE.

WILLIAM GENDER, OF MILWAUKEE, WISCONSIN.

DESIGN FOR A SHEET-METAL VESSEL.

SPECIFICATION forming part of Design No. 33,366, dated October 16, 1900.

Application filed September 16, 1899. Serial No. 730,777. Term of patent 7 years.

To all whom it may concern:

Be it known that I, WILLIAM GENDER, a citizen of the United States, residing at Milwaukee, in the county of Milwaukee and State of Wisconsin, have invented and produced a new and original Design for Sheet-Metal Vessels, of which the following is a specification, reference being had to the accompanying drawings, forming a part thereof.

Figure 1 is a side elevation of a sheet-metal vessel, showing my new design; and Fig. 2 is a sectional view taken in a plane indicated by the line 2 2, Fig. 1.

As shown in the drawings, the leading or material features of my design consist of corrugations A A, radiating from the scalloped margin of a substantially-circular figure B in the bottom and extending upwardly from the

bottom and terminating at their upper ends in a scalloped outline, a plain band C between the rim or upper edge of the vessel and the upper ends of said corrugations, and a circumferential bead D, passing horizontally around the vessel above its base and intersected by the corrugations A A.

Having thus described my invention, what I claim as new, and desire to secure by Letters Patent, is—

The design for a sheet-metal vessel, substantially as herein shown and described.

In witness whereof I hereto affix my signature in presence of two witnesses.

WILLIAM GENDER.

Witnesses:

CHAS. L. GOSS,
C. W. DENICKE.
